[57] ABSTRACT

The present invention concerns the use of compounds
having the formula

wherein R₁ and R₂ are each hydrogen, methyl, ethyl, propyl, isopropyl, halogen or methoxy, and acyl derivatives thereof as agents for the treatment of psoriasis and other dermatological diseases with increased epidermal proliferation, said agents being incorporated with a dermatologically acceptable carrier.

6 Claims, No Drawings

PREPARATION FOR TREATING PSORIASIS

The present invention relates to a preparation for treating psoriasis and other dermatological diseases with increased epidermal proliferation.

It has been known since the first World War to use the three-nuclear aromatic compound 1,8,9-trihydroxyanthracene for this purpose. This compound is highly efficient against skin diseases of the aforementioned type in relatively low concentrations. One disadvantage with this compound, however, is that even when incorporated in low concentrations in a composition intended to be applied to the skin, it has a strongly irritating effect and, furthermore, the portions of the skin treated therewith become discoloured, which is a disadvantage from a cosmetic point of view. When using a preparation of the type aforescribed and forming part of the present state of the art, it is necessary to experiment with preparations containing low percentages of the active substance. It is usual practice to begin with an ointment containing 0.05 % of active substance. It is often necessary to cease treatment when an irritation effect is reached. Very few people suffering from psoriasis can withstand treatment with an ointment containing more than 0.5 % of the mentioned anthracene derivative. The aforementioned cosmetic disadvantage exhibited in discolouring of the irritated portions of the skin is accompanied with a technical disadvantage, inasmuch as the clothes of the patient and the bedclothes in contact with said patient readily become stained. These stains are very difficult to remove by washing.

It is also known to use steroid preparations for treating psoriasis. The steroids, however, have strong medicinal disadvantages, since they have a skin-thinning effect and will facilitate the occurrence of infections.

In conjunction with the advent of the present invention, it has been found that hydroxy-substituted phenanthrenes having the formula

wherein R₁ and R₂ are each hydrogen, methyl, ethyl, propyl, isopropyl, halogen or methoxy, and acyl derivatives of said hydroxy-substituted phenanthrenes have a good effect against psoriasis when administered in the form of an externally applied preparation without at the same time causing irritation and/or cosmetic unfavourable discolouration of the skin or textiles coming into contact with the patient, provided that the content of the active substance in the preparation is between 0.1 and 10 %, preferably between 0.5 and 5 % calculated on the weight of the preparation. A preparation containing hydroxy-substituted phenanthrenes has thus a greater pharmaceutical scope than preparations based on trihydroxy-substituted anthracene.

Examples of the acyl derivative of the aforementioned compounds include acetyl and propionyl derivatives.

The present preparation may have the form of an ointment, a liniment, a solution, an emulsion or a

cream. The vehicle may also be in powder or paste form.

The invention will now be illustrated more clearly with reference to the following examples:

EXAMPLE 1

A mixture was prepared from the following constituents:

10	2-phenanthrol	9.0 g.
	petrolatum	180 g.

The resulting mixture represented a preparation in the form of an ointment for treating psoriasis.

EXAMPLE 2

A mixture was prepared from the following constituents:

20	1-phenanthrol	0.07 g.
	petrolatum	7.0 g.

The resulting mixture represented a preparation in the form of an ointment for treating psoriasis.

EXAMPLE 3

A mixture was prepared from the following constituents:

30	2-phenanthrol	1.2 g.
	petrolatum	120 g.

The obtained mixture represented the preparation in the form of an ointment for treating psoriasis.

EXAMPLE 4

A mixture was prepared from the following constituents:

40	1-phenanthrol	0.5 g.
	petrolatum	17 g.

The obtained mixture represented a preparation in the form of an ointment for treating psoriasis.

EXAMPLE 5

A mixture was prepared from the following constituents:

55	2-phenanthrol	1.0 g.
	monostearin	2.0 g.
	adeps solidus	0.2 g.
	cholesterol	0.2 g.
	Amifisol ^{TM}	0.5 g. (diethanolamine complex of cetyl phosphate, marketed by the company Givaudan, Switzerland)
60	sodium chloride	0.1 g.
	lactic acid	1.0 g.
	betaine hydrate	1.0 g.
	carbamide	2.0 g.
	water to total	20 g.

The obtained mixture represented a preparation in the form of a cream for treating psoriasis.

EXAMPLE 6

A mixture was prepared from the following constituents:

2-phenanthrol	9.0	g
liquid paraffin	75	g
Arlacel 481 ^(a)	30	g (glycerolsorbitan fatty acid esters, marketed by the company Atlas Chemie, Germany)
lactic acid	3	g
glycerol	9	g
water to total	300	g.

The obtained mixture represented a preparation in the form of a cream for treating psoriasis.

Preparations according to the present invention have been tested in the relation to the previously known substance 1,8,9-trihydroxyanthracene (dithranol) with respect to discolouration and irritation of the skin. 1,8,9-trihydroxyanthracene has been tested in the form of two preparations, the composition of which lies within the range of what is normal when carrying out medical treatment with this compound. The results obtained are recited in the following Table:

preparation	number of cases treated	positive clinical effect	skin irritation	discolouration
1	5	5	0	0
2	5	5	0	0
3	5	4	2	5
4	5	4	5	5
5	5	1	0	0

Preparation 1 = 5% 2-phenanthrol in petrolatum (Vaseline) according to Example 1
 " 2 = 1% 1-phenanthrol in petrolatum according to Example 2
 " 3 = 0.1% dithranol in petrolatum
 " 4 = 0.5% dithranol in petrolatum
 " 5 = petrolatum.

wherein R₁ and R₂ are each a member selected from the group consisting of hydrogen, methyl, ethyl, propyl, isopropyl, halogen, and methoxy; and a dermatologically acceptable carrier, said per cent being calculated on the total weight of the preparation.

2. A preparation as claimed in claim 1, wherein the compound is 1-phenanthrol.

3. A preparation as claimed in claim 1, wherein the compound is 2-phenanthrol.

4. A preparation as claimed in claim 1, wherein the content of the compound is in the range of from 0.5 to 5 per cent.

5. A preparation as claimed in claim 1, wherein the preparation is in the form of an ointment.

6. A method of treating psoriasis in a human suffering therefrom which comprises applying to the diseased skin of said human an effective amount of a preparation comprising 0.1 - 10 per cent of a compound having the formula

What is claimed is:

1. A preparation for the treatment of psoriasis comprising 0.1 - 10 per cent of a compound having the formula

40 wherein R₁ and R₂ are each a member selected from the group consisting of hydrogen, methyl, ethyl, propyl, isopropyl, halogen, and methoxy; and a dermatologically acceptable carrier, said per cent being calculated on the total weight of the preparation.
